ADJUSTABLE ROPE HALTER

Edward Hethcote, Holyoke, Colo.

Application April 16, 1935, Serial No. 16,682

1 Claim. (Cl. 54—24)

This invention relates to a fixture for rope halter, the general object of the invention being to provide a simple device for holding the rope in position forming a halter, the device being so formed that the halter can be made in less time than with the use of rope only and it makes the halter adjustable to suit animals of different sizes and the parts stay in adjusted position after being adjusted.

10 This invention also consists in certain other features of construction and in the combination and arrangement of several parts, to be herein-after fully described, illustrated in the accompanying drawing and specifically pointed out in the appended claim.

15 In describing the invention in detail, reference will be had to the accompanying drawing wherein like characters denote like or corresponding parts throughout the several views, and in which:—

20 Figure 1 is a view showing a rope halter on an animal and showing how the device holds the parts of the rope together.

Figure 2 is a view of the halter removed.

25 Figure 3 is an edge view of the device.

As shown in this drawing the device A is composed of a loop forming part 1, a loop forming part 2 and a part 3 connecting the two loop forming parts together, this part 3 extending diagonally from the part 1 to the part 2 and the part 2 being set more on an incline than is the part 1. As it will be seen, a portion of the rope is looped to form a headpiece 6. The free end 5 is bent upon itself as at 4 to form a loop, which passes through the loop-forming part 2, with the bight of the loop 4 passing over the shank part 3. This free end 5 of the rope is adjustably secured to a portion of the headpiece 6 by means of loops 7. There is thus formed the nose piece 8. The other free end 9 of the rope passes through the loop-forming part 1, which retains the headpiece and the nose piece at the desired length.

45 As shown in Figure 1 the device is placed at the lower portion of one side of the face of an animal with the part 3 substantially vertical and the part 2 sloping upwardly and outwardly so that the loop 4 in the rope can pass through the part 2 and around the part 3. The part 1 slopes downwardly and toward the neck of the

animal. The part 2 is elongated transversely of the length of the device, while the part 1 extends lengthwise of the device.

With this device a halter can be quickly made and quickly adjusted to fit the head of different sizes of animals and it stays in place after being adjusted. The rope wearing against a smooth surface will wear much longer than with rope against rope as in halters as now constructed. With this device the halter can be readily adjusted even when wet, where it is a difficult matter to adjust an all rope halter. The device can be quickly removed from a worn halter and used on a new one.

It is thought from the foregoing description that the advantages and novel features of the invention will be readily apparent.

It is to be understood that changes may be made in the construction and in the combination and arrangement of the several parts, provided that such changes fall within the scope of the appended claim.

What is claimed is:—

A halter of the class described comprising a single length of flexible material looped to form a headpiece, one free end of the flexible material being bent upon itself to form a loop at the terminal of the headpiece, said free end having loops formed thereon to adjustably secure the same to a portion of the headpiece to form a nose piece, and means for retaining the flexible material in halter-forming position, said means comprising a substantially vertically arranged intermediate shank part, a closed loop-forming part extending upwardly and outwardly from the shank part, said loop-forming part having the loop in the flexible material pass therethrough with the loop partly passing around the shank part, and a substantially oval-shaped loop-forming part connected to the lower end of the shank part, said second-mentioned loop-forming part being arranged at a less inclination from the vertical shank part than is the first-mentioned loop-forming part, whereby the second-mentioned loop-forming part is adapted to receive the said other free end of the flexible material to automatically adjust the length of the headpiece and the nose piece of the halter.

EDWARD HETHCOTE. 50
